UNITED STATES PATENT OFFICE.

JAMES P. SNEDDON, OF BARBERTON, OHIO, ASSIGNOR TO THE BABCOCK & WILCOX COMPANY, OF NEW YORK, N. Y., A CORPORATION OF NEW JERSEY.

SUPERHEATER-BOILER.

1,045,207.

Specification of Letters Patent. Patented Nov. 26, 1912.

Application filed March 6, 1907. Serial No. 360,850.

REISSUED

To all whom it may concern:

Be it known that I, JAMES P. SNEDDON, of Barberton, Summit county, Ohio, have invented a new and useful Superheater-
5 Boiler, of which the following is a full, clear, and exact description, reference being had to the accompanying drawings, in which—

Figure 1 is a sectional side elevation showing one form of superheater constructed in accordance with my invention; in combination with a boiler. Fig. 2 is a front elevation of the same, one half being in section; and Figs. 3 and 4 are broken detail views 15 showing the arrangement and connections of the superheater-headers or boxes.

My invention relates to the class of superheaters and superheater boilers, and is designed particularly to provide a connection 20 from the steam space of the boiler to the inner portion of the superheater-header or supply-chamber, with the use of an external supply-pipe outside the setting.

It is also designed to provide for proper 25 drainage of superheater boxes or headers, to increase the superheater tube surface, and provide an efficient and long-lived apparatus.

In the drawings, wherein I show my invention as applied to a four-drum Stirling boiler, 2, 3 and 4 represent steam and water drums connected by banks of tubes 5, 6 and 7, with a mud-drum 8. The usual baffles 9, 10 and 11 extend along the rear portions 35 of these banks of tubes; and the drums 2 and 3 are preferably connected by the water circulators 12 and steam circulators 13. Any steam generated in the drum 4 passes through tubes 14 to a steam space of drum 40 3, whence it goes to the superheater.

In the form shown, the superheater is located in the second pass and between the baffle 9 and the middle bank of tubes 6. It consists of U-shaped tubes 15, connecting 45 the headers or boxes 16 and 17, which extend transversely and preferably from side to side of the setting. In order to increase the superheating surface I preferably extend the front leg of the tubes beyond the 50 other leg. I also preferably provide a baffle-shelf 18 between the rear leg of the superheater and the tubes 6, thus dividing the gases and causing them to flow down among the tubes 6 and the superheater tubes 15.

The steam-supply pipe 19 leads down 55 from the drum 3 externally of the setting and is secured preferably by a flanged side connection to the projecting end portion of an added dead-header 20 which extends parallel with and slightly below the header 17. 60 This dead-header 20 is connected by suitable nipples 21 with the inner end portion of the superheater inlet-header 17, thus supplying steam to the superheater tubes which are farthest from the supply pipe. This 65 peculiar connection prevents short-circuiting of the steam through the tubes of the superheater nearest the supply pipe, which would cause burning out of the inner superheater tubes when the boiler was operated 70 considerably below its capacity. The other or superheater outlet-header 16 also preferably projects beyond the side wall and has flanged side connection with the outlet pipe 22 for the superheated steam. The superheater headers are preferably provided at 75 their outer ends with hand-hole covers *b* and drain pipes *a*. The inner ends of the headers are also arranged an inch or two higher than the outer ends to provide proper drainage.

I have illustrated the superheater boiler as arranged in duplex form, with two units arranged side by side, having a common inner wall, and the superheater headers projecting in opposite directions through the opposite side wall. The construction may, however, be used in one or any number of units.

The advantages of my invention result 90 from the use of the steam supply connection or dead-header, which is connected to the inner portion of the inlet header or box. Also from the side connections on the projecting ends of the headers, which provide 95 for access and drainage at the end; and further from the arrangement of the superheater legs, baffle-shelf, etc.

As to the features of the superheater proper, in their broader novelty they may be 100 applied to various types of superheaters, arranged in different parts of the boiler setting.

Many changes may also be made in the form and arrangement of the boiler, setting, 105 &c., without departing from my invention.

I claim:

1. A steam superheater having headers

- within the boiler setting, tubes connecting said headers, a dead-header adjacent to one of said headers and within the boiler setting, an inlet pipe leading from the steam space 5 of the boiler to one end of the dead-header, a connection between the dead-header and the adjacent header, and steam off-take pipe leading from the other header; substantially as described.
- 10 2. A steam superheater having headers within the boiler setting, tubes connecting said headers, a dead-header adjacent to one of said headers and within the boiler setting, an inlet pipe leading from the steam space 15 of the boiler to the dead-header at one side of the setting, a plurality of connections between the dead-header and the adjacent header at the other side of the boiler setting, and an off-take pipe communicating 20 with the other header, the off-take pipe and the communication between the dead-header
- and the header being at opposite ends of the superheater; substantially as described.
3. A steam superheater having headers within the boiler setting, and extending beyond said setting, and tubes connecting said headers within the boiler setting, a dead-header adjacent to the lower header and extending beyond the boiler setting, an inlet pipe exterior of the boiler setting leading 25 from the steam space of the boiler to the dead-header, connections between the dead header and the lower header and an off-take pipe exterior of the boiler setting communicating with the upper header; substantially 30 as described.
- 35

In testimony whereof, I have hereunto set my hand.

JAMES P. SNEDDON.
